APPARATUS FOR ILLUSTRATING
ECONOMIC LAWS

James D. Mooney, Oyster Bay, N. Y.

Application May 22, 1947, Serial No. 749,645

2 Claims. (Cl. 35—24)

1

This invention relates to improvements in apparatus designed to illustrate the laws of economics by physical analogies. Apparatus of this type were set forth in my U. S. Letters Patent Nos. 1,989,878 and 2,281,368. The object of the present invention is to provide improved means for giving the mind physical pictures to aid in grasping abstract conceptions.

While in my earlier inventions the various mechanical actions representing economic forces were usually set into motion by means of manually operated controls, the demonstrations are made vastly more effective and convincing by providing suitable mechanisms which automatically vary the physical factors and thus give a continuous and automatic representation of the interplay and interaction of economic forces.

The subject chosen for illustration in the present invention is the series of interrelated forces and reactions pertaining to supply, demand and price; the all-embracing name commonly used for these relations being "The Law of Supply and Demand." Included in this so-called law are the facts that:

(1) Prices depend upon supply and demand. They tend to rise if supply decreases or if demand increases. Conversely, they tend to fall if supply increases and demand decreases.

(2) Supply and demand are affected by prices. High prices tend to cause an increase in supply and a decrease in demand. Conversely, low prices tend to cause a decrease in supply and an increase in demand.

In the form of construction shown in my earlier patents, there was no automatic control of the flow of liquid representing "Supply" to correct variations in price. In actual business, an increase in price increases profits and stimulates production. It is highly desirable, therefore, that apparatus designed to represent business cycles and economic laws indicates such a relationship.

A further deficiency in the mode of operation of the earlier forms of my apparatus was the fact that apart from a manually controlled valve, any variation in flow of liquid from the "Inventory" tank was solely the result of changes in the hydrostatic head of the "Inventory" receptacle. Such variations in liquid flow were much more sluggish than the variations in flow of goods in the commodity markets. Further, there was never any over-compensation, such as occurs in actual economic practice. Practical business experience has demonstrated time and again that when inventories are high and prices low, the

demand created by the low prices acquires sufficient momentum to reduce inventories to the point at which there becomes an acute shortage. There is then a quick reaction which carries prices above their stable or average value. In general, demand keeps up longer than it should to bring inventories down and prices up to their proper levels. Supply likewise tends to keep up longer than it should to bring inventories up and prices down to their proper levels.

According to the present invention, therefore, valves are provided in both the "Supply" and "Demand" lines which are automatically opened wider and closed further by the rise and fall of the "Inventory" receptacle (i. e., price changes). When the latter sinks, indicating an increase in inventories and a corresponding decrease in price, the "Supply" valve is closed further and the "Demand" valve is opened wider so that the over-stocked and under-priced condition is rapidly corrected. When the "Inventory" receptacle rises, the reverse takes place. The actual distance the "Inventory" receptacle rises and falls is not very great, so it is not always readily apparent when it stops moving in one direction preparatory to moving in the other.

Another object of the invention, therefore, is to provide a means for giving visual indication of whether or not the receptacle is moving and, if so, in which direction it is moving.

The present invention covers the mechanisms employed to portray, by graphic analogy, the above economic actions and reactions. Basically, the mechanism comprises:

(a) A receptacle containing a variable amount of liquid representing the stocks or inventories of goods available on the market.

(b) Means for introducing into this receptacle a stream of liquid representing the supply of goods for sale on the market.

(c) Means for drawing from the receptacle a stream of liquid representing the demand for goods at the prevailing market price.

(d) A float which supports the "Inventory" receptacle and rises and falls as the amount of liquid in such receptacle decreases and increases.

(e) Various mechanisms and devices for automatically and/or manually varying and controlling the rates of flow of the "Supply" and "Demand" streams in various manners aimed to illustrate by analogy the interactions of economic forces in true life.

Conveniently, such mechanisms and devices include electric motors wound for operation in either direction. These motors open or close

valves in the "Supply" and "Demand" pipes according to the direction of flow of electric current through such motors. The supply of current to such motors is controlled by a series of switches opened and closed by vertical movements of the float produced by changes in the amount of liquid in the "Inventory" receptacle.

Operation of the apparatus is as follows: Water is forced by a centrifugal pump through a pipe and valve to a header on the "Supply" shelf. As the pump is of the centrifugal type, the quantity of liquid it delivers may be controlled by a valve in its delivery pipe. The valve in the "Supply" line is motor-driven and is actuated in the proper manner in accordance with impulses originating from and depending upon the prevailing conditions of "Price." The mechanical and electrical arrangements are such that, in general:

(a) The "Supply" valve tends to open when the "Price" is high.

(b) The "Supply" valve tends to close when the "Price" is low.

The liquid, after pouring from the "Supply" header and chute, flows into the "Inventory" receptacle. It then flows, by force of gravity, from the receptacle by way of the "Demand" pipe. Such gravity flow is dependent on the head of liquid in the receptacle.

It has been found desirable to accentuate the effect of gravity by a "Demand" valve in this pipe line. The valve is motor-driven and the mechanical and electrical arrangements are such that, in general:

(a) The "Demand" valve tends to open when the "Price" is low (i. e. when the amount of liquid in the receptacle is large).

(b) The "Demand" valve tends to close when the "Price" is high (i. e. when the amount of liquid in the receptacle is small).

After flowing from the "Demand" pipe, the liquid finds its way back to the reservoir from which it is again circulated through the same cycle.

The rise and fall of price are represented by the rising and falling motion of a float which supports the dead weight of the "Inventory" receptacle. When a large amount of liquid fills the receptacle, representing large inventories of goods, the weight in the receptacle causes the float to sink deeply in its supporting fluid, this action typifying falling prices. Conversely, when the "Inventory" receptacle is nearly empty, representing a condition of scarcity of goods available for sale, the float supporting the receptacle rises, typifying rising prices.

Various means may be employed for opening and/or closing the "Supply" and "Demand" valves as the receptacle moves up and down. Preferably such means include mechanical connections to the float for actuating cam surfaces which can be pre-set to operate electrical switches which will energize the valve-operating motors in accordance with predetermined patterns. In this manner the conditions and variations pertaining to "Price" can be made to cause the streams of "Supply" and "Demand" to respond in the correct manner.

As an auxiliary and manual means for controlling the actions of the valves—as when it is desired to demonstrate some particular economic phenomenon—a system of manually operated electrical push buttons may be provided. One suitable arrangement comprises six push buttons: three for "Supply" and three for "De-

mand." In each set of three one button causes the actuating motor to increase the valve opening, another to decrease it, while the third renders the motor inoperative in the event it is desired to demonstrate the effects of blocking or interfering with certain economic forces.

The electrical circuits are so arranged that the push buttons take precedence in operation over the cam-operated switches.

It is also advantageous to provide overtravel limit switches to prevent the motor from driving the valves beyond limits where mechanical damage might be incurred. They also perform the function of making it possible to pre-select the maximum and minimum degrees of valve openings beyond which the valves should not travel for the most effective presentation.

One suitable form of construction is illustrated, by way of example, in the accompanying drawings, wherein:

Fig. 1 is a front elevation of the apparatus as a whole;

Fig. 2 is a diagrammatic front elevation of the apparatus showing the liquid circulation means;

Fig. 3 shows the wiring diagram for the valve-actuating motors;

Fig. 4 is a more or less diagrammatic view of the float, "Inventory" receptacle and the mechanism and switches operated by movements of the former;

Fig. 5 is a plan view of the push button panel;

Fig. 6 is a diagram showing the ranges over which the various motor-controlling switches are operative;

Fig. 7 is a detail view on an enlarged scale of part of the mechanism shown in Fig. 4; and

Fig. 8 is a section on the line 8—8 of Fig. 4.

The apparatus illustrated comprises a cabinet 40 having a wall 11 extending upwardly from its rear side. This cabinet performs a dual function; first it acts as a support for parts of the apparatus, such as the "Stable money" tank 12 and the "Demand" distributor 13, and second it serves as a housing for the water reservoir 14, pump 15 and motor 16.

The liquid circulating system is shown in Fig. 2. Water is forced by pump 15 through pipe 17, valve 18 to a header 19 on the "Supply" shelf 20. From the header 19 is a series of outlets 24, three as shown. Adjacent to the first of these are miniature figures and models representing the delivery of barrels and packing cases containing manufactured goods. Over the second is the representation of an oil derrick as symbolic of natural mineral products. Adjacent the third is a farm wagon to indicate the supply of wheat, cotton and other farm products.

Water discharged from these outlets flows forwardly over the shelf and down its front where an inclined trough 25 collects the water from all three outlets and discharges it as a single stream through a spout 26. Beneath this spout is an "Inventories" receptacle 27 of glass or other transparent material mounted on top of the float 28 in the tank 12. From the bottom of receptacle 27 extends a pipe 28a for discharging water into the "Demand" distributor 13.

The "Demand" distributor consists of a cylinder 33 from which lead a series of outlet pipes 34. These pipes discharge into a series of downcasts 35, the lower ends of which are above the level of the water in the reservoir 14. Around 75 the downcasts is the representation of a retail

store to simulate the distribution of different classes of goods to the consuming public. The pump 15 is of the centrifugal type as that type delivers water at a constant pressure rather than at a constant volume. With a pump having these characteristics, the volume of water delivered thereby is roughly proportional to the opening of the valve 18. As will be explained later, the operating mechanism for valve 18 is set so that the valve never completely closes or opens. Hence, to stop the operation of the apparatus, the switch 36 in the circuit of motor 16 must be opened.

When the volume of liquid in the receptacle 27 representing "Inventory" increases due to the rate of flow from the "Supply" shelf exceeding the rate of flow from the receptacle 27 to the "Demand" distributor, the float 28 sinks in the "Stable money" tank 12. When this happens marketwise, the price of the goods drops. Hence, means are provided for indicating the depth of submergence of the tank in terms of price. Such means include a pointer 40 attached to the float and a "Price" scale 41 graduated so that the price is a maximum when the receptacle 27 is empty and a minimum when it is full.

As the receptacle 27 is on top of the float 28, the combination is top-heavy. Means are, therefore, required for maintaining the float in upright position without interfering with its vertical rise and fall with changes in the amount of liquid in the receptacle 27.

According to the present invention, this is accomplished by a parallel linkage support extending through a slot 43 in the wall 11, shown more particularly in Fig. 4. A bar 44 is provided having two cross-rods 45 and 46 passing therethrough and rigidly connected thereto. Above the bar 44 is a link 47 likewise provided with cross-rods 48 and 49 rigidly connected thereto. The ends of rods 45 and 48 are journaled in bearings (not shown) mounted on the rear side of the wall 11. The ends of rods 46 and 49 are similarly journaled in bearings (not shown) mounted on the back wall of the float 28. As rods 45 and 48 are spaced apart the same distance as 46 and 49, and are located in parallel vertical planes, the float is maintained in upright position at all times irrespective of the extent to which it is submerged in the liquid in the tank 12. Lateral wobble is eliminated by the fact that the bearings for the ends of the rods 45, 46, 48 and 49 are spaced apart a considerable distance.

The back wall of the float is spaced well forward of the rear edges of the top and sides of the float for various reasons. In the first place, it enables the distance between the rods 45 and 48, on the one hand, and the rods 46 and 49, on the other, to be made greater than would otherwise be the case. This flattens out the curved path of movement of the float. In the second place, it reduces the effective cross-section of the float and hence increases the variation in the depth of submergence of the float for any given change in the amount of fluid in the receptacle 27. In other words, it makes the apparatus more responsive to variations in the ratio between supply and demand. On the other hand, reduction in the effective cross-section of the float reduces its weight-supporting power. To overcome that objection, a counterweight 39 is provided to produce a lifting force nearly equal to the weight of the float and receptacle when the latter is empty.

Movement of the rod 44 controls the opening and closing of the valves 18 and 29. Before this

control mechanism is described, the valve operating means and the electrical circuits by which such means are controlled will be described.

The stem of valve 29 has on its rear end a worm wheel 50 driven by a worm 51 on a shaft 52 carrying another worm wheel 53 in mesh with a worm 54 on the shaft 55 of a motor 56. Similar operating mechanism (not shown) is provided for valve 18.

The control circuits for the two motors are identical so only one is shown diagrammatically in Fig. 3. The armature winding is indicated at 60. To permit reversal there are two field windings 61 and 62. For convenience in description, it will be assumed that it is the "Demand" valve which is being operated and that the winding 61 is the one required for opening the valve. There are three switches in series with this winding. Switch 63 is the limiting switch which is normally closed and is opened only when the valve nears its fully open position. Switch 64 is closed automatically when the float sinks (inventories rising and prices dropping) to cause the "Demand" valve to open. Switch 65 is normally open but is arranged so that it may be closed manually by a push button whenever it is desired to increase "Demand" arbitrarily.

Switches 70, 71 and 72 have exactly analogous functions with respect to the field winding 62 which, on energization, causes the valve to close. In series with the armature there is yet another switch 66 which is normally closed but arranged so that it may be opened manually whenever it is desired to hold "Demand" constant arbitrarily.

The push button panel is shown in Fig. 5. The buttons 65, 66 and 72 are the operating members of the switches of the same numbers on Fig. 3.

The motor, control circuits and push button switches for operating valve 18 are the same as those described in connection with valve 29, so that no illustration or description thereof is necessary.

The switches and circuits above described take care of operation of the valves. The apparatus also includes a series of signal lamps arranged alongside of a number of descriptive legends explaining what is happening, economically speaking. As shown in Fig. 1, there are five of such lamps 75, 76, 77, 78 and 79. For operating these lamps four switches 80, 81, 82 and 83 are provided. Two of these switches 80 and 83 are electrically connected so that they operate as single-throw switches, while the other two are double-throw connected. Conveniently, these switches are of the snap-action type described in Eaton U. S. Patent 2,172,673. These switches have a contact arm which snaps back and forth between two contact points as pressure is applied to or taken off a pin attached to such arm and projecting beyond the body of the switch.

The circuit diagram is shown in Fig. 9. It will be noted that lamp 77 is in series with both switches 81 and 82 so that if either switch is thrown to light its corresponding lamp 76 or 78, the circuit through lamp 77 is broken.

Lamps 76 and 78, as their corresponding legends indicate, represent movements in prices. Lamp 77 represents stable conditions with supply and demand substantially in balance. Lamps 75 and 79 indicate excessively high and abnormally low prices.

There is another switch 85 in series with lamp 77 which is closed only when the price is within the range 80 to 84. This additional switch is used to prevent the lamp 77 lighting when conditions

are more or less stationary but at the same time unduly high or low.

One of the functions of the present apparatus is to give visual signals indicating not only movement of prices but also the direction in which such movement is taking place. Another function is to give a visual signal indicating lack of movement or stable prices.

The mechanism devised for this purpose consists essentially of a pivotally mounted part normally centered by a spring or springs between two contact points on an arm pivoted to swing about the same axis as said part and connected to the moving member whose movement is to be indicated. A dash-pot is connected to said part to slow down the movement of the latter so that on all movements of the arm, except the very slowest, the dash-pot will offer greater resistance to such movement than the centering springs so that said part will lag behind the arm and consequently contact one or other of the contacts. Which contact is engaged depends upon the direction in which the arm moves. As soon as the arm comes to rest, the springs slowly move the dash-pot until such part is once more centered between the two contacts.

In the particular construction illustrated, a disc 90 is fixedly mounted on a rotatable shaft 91 to which is rigidly connected a rocker arm 110. See Fig. 7. One end of this arm is connected to the piston rod 111 of a dash-pot 112. The other end of the arm 110 carries a counterweight 113 to offset the weight of the piston and piston rod of the dash-pot.

Loosely mounted on the shaft 91 is another rocker arm 92, pivotally connected at 93 to the link 94 which, in turn, is connected at 95 to the arm 44. Consequently, vertical movements of the float produce corresponding angular movements of the rocker arm 92.

On the outer end of rocker arm 92 are mounted the snap switches 81 and 82, previously referred to, with their operating pins in contact with or closely adjacent to the top and bottom, respectively, of the rocker arm 110. When such end of the arm 92 moves upwardly, the switch 81 is closed and the adjacent end of the rocker arm 110 is moved upwardly. A downward movement of such end closes the switch 82. Springs 115 and 116 are provided for the purpose of returning the rocker arm 110 into parallelism with the arm 92 against the resistance offered by the dash-pot 112. In this position the switches 81 and 82 are positioned as shown in Fig. 9.

Arranged around the periphery of the disc 90 are seven cams 100, 101, 102, 103, 104, 105 and 106 for operating switches 85, 71, 64, 83, 80, 88 and 89, respectively. Conveniently the cams are

mounted so that their position may be adjusted circumferentially with respect to the disc to produce operation of the switches at any desired angular position of the disc.

5 Subject matter disclosed but not claimed in this application is claimed in divisional application Serial No. 53,561 filed by applicant on Oct. 8, 1948.

I claim:

- 10 1. A device for illustrating economic laws, comprising a tank containing liquid, a float therein, a liquid receptacle carried by said float, means for admitting liquid to and discharging liquid from such receptacle simultaneously to represent commodity supply and demand, a price scale at one side of the float and receptacle, a pointer carried by the latter for indicating on the scale vertical movements of the float and receptacle, a valve for controlling the rate of such admission 15 and a reversible electric motor for opening and closing said valve, a switch therefor adapted to be closed by the float to run the motor in one direction when the float rises above a predetermined height and a second switch therefor 20 adapted to be closed by the float to run the motor in the opposite direction when the float falls below a predetermined height.
- 25 2. A device for illustrating economic laws, comprising a tank containing liquid, a float therein, a liquid receptacle carried by said float, means for admitting liquid to and discharging liquid from such receptacle simultaneously to represent commodity supply and demand, a price scale at one side of the float and receptacle, a pointer carried 30 by the latter for indicating on the scale vertical movements of the float and receptacle, a valve for controlling the rate of such discharge and a reversible electric motor for opening and closing said valve, a switch therefor adapted to be closed 35 by the float to run the motor in one direction when the float rises above a predetermined height and a second switch therefor adapted to be closed by the float to run the motor in the opposite direction when the float falls below a predetermined 40 height.
